UNITED STATES PATENT OFFICE

130,375

DESIGN FOR A LIPSTICK SPREADER

Charles E. Zimmerman, Chicago, Ill.

Application August 24, 1940, Serial No. 94,608

Term of patent 7 years

To all whom it may concern:

Be it known that I, Charles E. Zimmerman, a citizen of the United States, residing at Chicago, in the county of Cook and State of Illinois, have invented a new, original, and ornamental Design for a Lipstick Spreader, of which the following is a specification, reference being had to the accompanying drawing, forming a part thereof.

In the drawing:

Figure 2 is a perspective view showing the cap and the body of the spreader in separated relation.

The characteristic features of the design reside in the lipstick spreader illustrated having an applicator portion of the specific configuration shown in Figure 3.

I claim:

The ornamental design for a lipstick spreader, substantially as shown and described.

CHARLES E. ZIMMERMAN.
